UNITED STATES PATENT OFFICE.

FRANK J. VLCKEK, OF CLEVELAND, OHIO, ASSIGNOR TO THE VLCKEK TOOL COMPANY,
A CORPORATION OF OHIO.

RIPPING BAR AND METHOD OF MAKING SAME.

Application filed July 8, 1922. Serial No. 573,564.

To all whom it may concern:

Be it known that I, FRANK J. VLCKEK, a citizen of the United States, residing at Cleveland, in the county of Cuyahoga and State of Ohio, have invented certain new and useful Improvements in Ripping Bars and Methods of Making Same, of which the following is a specification.

This invention relates to ripping-bars and method of manufacturing the same.

The main object of the invention is to provide a ripping-bar which may be manufactured from stock bar material of octagonal cross-section, and provide the hook thereof with a wide surface at its rear side to prevent sidewise tipping of ripping-bar when being used.

Another object of the invention is to provide at a low cost of manufacture a ripping-bar from octagonal stock and having said wide surface at the rear side of the hook.

With the above and other objects in view, the invention will be hereinafter fully described as illustrated in the accompanying drawing, and the novel features thereof will be distinctly pointed out in the appended claims.

In the drawings similar characters of reference are used to indicate corresponding parts.

Figure 1 is a side elevation of a ripping-bar made in accordance with this invention,

Fig. 2 is a cross-sectional view taken on line 2—2 of Fig. 1,

Fig. 3 is a view of the hooked end of the ripping-bar looking at the rear side thereof, and

Fig. 4 is a plan sectional view taken on line 4—4 of Fig. 1.

Referring to the drawings, 1 represents a ripping-bar manufactured from a single piece of stock bar material of octagonal cross-section, one end of which is formed into a chisel indicated at 2, and the other end is formed into a hook indicated at 3, as in the usual construction of ripping-bars. In forming the hooked end of the ordinary ripping-bar, it is common practice to bend the octagonal bar so that a pair of its opposite sides as 4 and 5 form inner and outer

surfaces respectively of the hook. When the comparatively narrow outer side 5 of the hook rests against a support as in practice, it is difficult for the operator and requires considerable exertion on his part to hold the 55 ripping-bar against rolling or tipping sideways on account of said narrow outer side not giving an adequate supporting surface for the hooked end of the bar.

This invention consists in providing the 60 outer side of the hook of the ripping-bar with a wide surface for giving adequate support to prevent said rolling or tipping sideways of the ripping-bar when being used. This is accomplished by compressing the 65 sides of the stock octagonal bar from which the ripping-bar is made to form a central rib 6 and oppositely extending lateral flanges 7 and 8, the rear sides of which provide a 70 wide supporting surface as at 9. For obtaining the widest flanges 7 and 8 possible from the stock of the octagonal bar, a central groove 10 is pressed out of the rear side of said flanges and the metal saved thereby increases the width of said flanges and gives 75 a wider supporting surface for the hooked end of the ripping-bar. It will be noted that although material is taken from the sides of the central rib 6 for forming the lateral flanges to give a wider supporting 80 surface for the hook, this hook has great strength due to said rib.

The hooked end of the ripping-bar terminates in a chisel 11 which may be bifurcated as at 12 for extracting nails, and it 85 will be understood that slight changes in the design of the ripping-bar and the details of construction may be made within the scope of the claims.

Having fully described my invention, 90 what I claim is:

1. A ripping-bar having a hook, and the hook having a central rib and oppositely extending flanges at the rear side of the rib to provide a supporting surface for the hook, 95 substantially as described.

2. A ripping-bar formed from a bar having an octagonal cross-section, a hook at one end of the bar, and the hook having a central rib and oppositely extending flanges at 100

the rear side of the rib to provide a support- and a longitudinal extending groove pressed in the rear side of the hook, substantially as described. 10

3. A ripping-bar having a hook, the hook having a central rib and oppositely extending flanges at the rear side of the rib to provide a supporting surface for the hook,

In testimony whereof, I affix my signature.

FRANK J. VLCHEK.
